(57) **CLAIM**

The ornamental design for house slippers, as shown and described.

DESCRIPTION

FIG. 1 is a perspective view of one of a pair of house slippers.

FIG. 2 is a right side view of the house slipper.

FIG. 3 is a left side view of the house slipper.

FIG. 4 is a top view of the house slipper.

FIG. 5 is a bottom view of the house slipper.

FIG. 6 is a front view of the house slipper, with the personalized name plate attached to the front of the house slipper.

FIG. 7 is a rear view of the house slipper; and,

FIG. 8 is a side cross sectional view of the house slipper along lines 8/8 of FIG. 4, with phantom lines indicating environment, said phantom lines not constituting part of the house slipper.
